UNITED STATES PATENT OFFICE

WARREN BREWER, OF NEW YORK, N. Y., ASSIGNOR TO THORNDIKE COMPANY, OF WEST WARREN, MASSACHUSETTS, A CORPORATION OF MASSACHUSETTS

DESIGN FOR A TEXTILE FABRIC

Application filed October 3, 1929. Serial No. 32,925. Term of patent 3½ years.

To all whom it may concern:

Be it known that I, WARREN BREWER, a citizen of the United States, residing in New York, county of New York, State of New York, have invented a new, original, and ornamental Design for a Textile Fabric, of which the following is a specification, reference being had to the accompanying drawing, forming part thereof.

The figure of the drawing is a plan view of a piece of textile fabric showing approximately one fourth of the motif constituting the design which is indicated by dot and dash lines, which section is repeated in the other three fourths in proper relation thereto.

I claim:

The ornamental design for a textile fabric substantially as shown and described.

WARREN BREWER.
